UNITED STATES PATENT OFFICE.

ALBERT J. RAU AND JULIUS A. RAU, OF CLIFTON, NEW JERSEY.

DYEING APPARATUS.

1,108,233.

Specification of Letters Patent. Patented Aug. 25, 1914.

Application filed March 4, 1914. Serial No. 822,359.

To all whom it may concern:

Be it known that we, ALBERT J. RAU and JULIUS A. RAU, citizens of the United States, residing at Clifton, New Jersey, have invented certain new and useful Improvements in Dyeing Apparatus, of which the following is a clear, full, and exact description.

This invention relates to dyeing apparatus, and a principal object of the present invention is to provide very simple means for facilitating the passing and guiding of a web of material when the dye is being applied thereto.

In the preferred form of the invention, a dye bath is employed and one of the objects of this invention is to provide improved means for facilitating the passage of the dye material into the fibers of the web which is being dyed.

A further object of the invention is to provide a very simple construction which will enable the web to be handled in a simple manner, and at the same time permit the development of an excess hydrostatic pressure on one side of the web which assists the passage of the dye liquor through the fibers of the fabric.

Further objects of the invention will appear more clearly hereinafter.

The invention consists in the general combination of parts and simplicity of details hereinafter described, all of which contribute to produce an efficient dyeing apparatus.

A preferred embodiment of our invention will be particularly described in the following specification, while the broad scope of our invention will be pointed out in the appended claims.

In the drawings, Figure 1 is a front elevation of the apparatus embodying our invention; Fig. 2 is a longitudinal section, certain parts being broken away; Fig. 3 is a vertical cross-section through the apparatus further illustrating the invention; and Figs. 4 and 5 show details.

Referring more particularly to the parts, we prefer to apply the dye in the form of a dye liquor, and this is preferably accomplished by providing a vat 1 which may be of rectangular form as shown, presenting heads 2 between which a drum 3 is mounted to rotate, said drum being fixed to a suitable shaft 4 which is rotated when the apparatus is in operation. The drum 3 is

preferably formed of end rings 5 connected by a cylindrical body 6 preferably consisting of a wire screen or similar material. We provide means for guiding the web 7 of the material to be dyed around the exterior of this drum so that it comes in contact with the dye bath in the vat. This guiding means preferably consists of two rollers 8 and 9, the axles 10 of which are preferably supported at the ends of hanger bars 11 pivotally supported at 12. The faces of these rollers 8 and 9 lie very close to the face of the drum so that either of the rollers may touch the face of the drum if slightly depressed. When one of these rollers is guiding the material onto the drum, the other is guiding it off of the drum.

In Fig. 3, we have illustrated the web 7 as passing from a supply-roll 13 of material to be dyed, and the web 7 passes around the inner face of the roller 9 and thence passes around the drum, being guided from the drum by the inner face of the roller 8 and thence being wrapped upon a delivery-roll 14. It should be understood that each of the rolls 13 and 14 may act as delivery or supply roll. The roll which is acting as a supply-roll is preferably held upon a fixed axis in elevated position, while the receiving or delivery roll such as the roll 14, preferably rests on the upper face of its corresponding guide-roll such as the roll 8. Now by a simple rotation of the shaft, the web 7 will be drawn off from the supply-roll 13 passed around on the underside of the revolving drum and then guided out of the vat. The weight of the delivery-roll 14 holds the roller 8 in contact with the drum so that the drum rotates it and the roller 8 in turn rotates the delivery-roll 14 in a direction to wind up the web upon it. The preferred means for enabling the rolls 13 and 14 to be operated in this way consists substantially of supporting arms 15 corresponding to each roller and rigidly attached to shafts 16. Any suitable means may be provided for counterweighting the rolls, for which purpose the shafts 16 may be provided with segments 17 meshing with pinions 18, which pinions are rigid with counterweight levers 19. These levers are provided with adjustable counterweights 20 which can be hung at different points on the lever, to compensate for differences in weight of goods, or removed entirely if necessary. The counterweight levers 19 are

2

preferably provided with clamping devices 21 which coöperate with slotted quadrants 22 so as to enable the arms 15 to be clamped if desired, in an elevated position and also 5 enabling the arms to be freely movable up or down when the clamping device 21 is loose. This arrangement enables the roll which is receiving the web to have its axle laterally movable, and this is desirable because as the roll turns, the layers of web 10 accumulate upon it and automatically raise the roll axis and the arms carrying the rolls. The rising of the delivery roll acts to move the counterweighted lever in opposite direction 15 so that increased power is exerted by said lever and the counterbalancing effect automatically maintained. It will be evident that if the delivery-roll 14 is counterweighted at all, the counterweight should 20 be very light so that there is always some weight on the roll 8 tending to bring about a good frictional contact insuring the proper rotation of the delivery-roll in winding the web upon it. The counterweights are particularly useful when a heavy supply-roll is 25 being raised on its arms 15 into a convenient position to facilitate the delivery of the web onto the drum. It is evident also that the pressure of the roll 14 on the roll 8 tends to 30 raise the supply guide-roll 9 out of contact with the drum. In order to facilitate the rotation of the rolls 8 or 9 from the drum 3, we prefer to provide the end rings 5 of the drum with grooves to receive bearing 35 rings 5^a of rubber or similar material having a good traction effect. Beyond the heads 2 the vat is formed with false heads 23, and the spaces between these false heads and the heads 2 form conduits 24 to facilitate 40 the circulation of the dye liquor.

While the apparatus described above can be used simply to pass a web through a bath in which the drum is immersed, we prefer to facilitate the dyeing apparatus by 45 means of an excess of the hydrostatic pressure on one side of the web, and we prefer to accomplish this by withdrawing the dye liquor constantly from the interior of the drum and returning it to the exterior. This 50 is preferably accomplished by providing openings 25 in the heads 2 preferably below the shaft 4, and the dye liquor is drawn outwardly through these openings in the direction of the arrows in Fig. 2 by means of 55 impellers or circulating wheels 26 carried by a shaft 27 and mounted in openings 28 in the heads 2. The impellers in one end of the vat are of opposite pitch from those of the opposite end so that at both ends of 60 the vat the apparatus operates to withdraw the liquor from the interior of the drum. As the heads 2 are very close to the ends of the drum, this circulation of the dye liquor produces a slight excess of hydrostatic pressure on the outer side of the drum 65

which assists in producing a flow of the dye liquor through the fibers of the web and renders the dyeing operation more effective.

In using the apparatus the web to be dyed is run from one roll around the drum 70 and is wrapped upon the opposite roll, and after the opposite roll is filled, the web can be repassed in the opposite direction around the drum and back to the roll which originally carried the web. This operation may 75 be repeated as often as desired.

While the drum 3 may have an outer shell 6 of any suitable construction of reticulated material, it is preferred that a built up construction such as that shown in Figs. 4 and 80 5 be employed. To this end, supporting spiders 3^a are fixed rigidly on shaft 4, inside the drum, and said shell 6 is secured rigidly to said spiders. Said built up screen construction comprises longitudinal bars or rods 85 6^a attached to the rims of said spiders 3^a. On these rods 6^a there is helically wrapped, about the drum, a continuous fine wire 6^b and then on this wire is laid an envelop or inner covering 6^c of coarse mesh wire gauze. Over 90 this is placed an outer covering 6^d of fine mesh wire gauze. An advantage of the gauze construction is that material can be dyed in one passage around the drum and there is no spotted effect produced. Also, in 95 the specific embodiment, the wire gauze is supported from the interior spiders of the drum and not directly by them, so that the gauze screen is properly supported on that side toward which the hydrostatic pressure 100 is exerted.

Although the apparatus has been described above with the idea that it is to be used in dyeing the goods, it is obvious that this apparatus may be used for charging the 105 goods or for washing goods, or for other purposes.

It is understood that the embodiment of the invention described above is only one of the many embodiments or forms the invention may take, and we do not wish to be limited in the practice of the invention nor in our claims to the particular embodiment disclosed.

What we claim as new is:—

1. In dyeing apparatus or the like, in combination, a vat for the dye-bath, a drum mounted to rotate in said vat, means for guiding the web of material to be dyed around the underside of said drum, and a delivery roller disposed above said vat and receiving the web directly therefrom, and means for producing an excess of hydrostatic pressure in said bath on the outer face of said drum.

2. In dyeing apparatus or the like, in combination, a vat for the dye-bath, a drum in the form of a screen mounted to rotate in said vat, means for guiding the web of material to be dyed around said drum, said

5 drum being adapted to be immersed in the bath within said vat, said drum having an open end, said vat having means for partially closing the end of said drum and having an opening communicating with the interior of said drum through the open end thereof, and means for withdrawing the dye liquor through the said opening and returning the same to the exterior of said drum to 10 create an excess hydrostatic pressure on the outer side of said drum.

15 3. In dyeing apparatus or the like, in combination, a vat for the dye bath, a drum rotatably mounted within said vat, means for guiding a web of material to be dyed onto 20 said drum, a supply-roll, means for supporting the same in a fixed position to deliver the web to said guiding means, and a delivery-roll arranged to receive the web after passing around said drum and arranged to be rotated by rotating said drum.

25 4. In dyeing apparatus or the like, in combination, a vat for the dye bath, a drum rotatably mounted within said vat, means for guiding a web of material to be dyed onto 30 said drum, a supply-roll for supporting the same in a fixed position to deliver the web to said guiding means, and a delivery-roll mounted to rotate about a laterally movable axle arranged to receive the web after 35 passing around said drum and supported by peripheral contact from beneath so as to rotate said delivery-roll to wind up the web thereupon.

40 5. In dyeing apparatus or the like, in combination, a vat for the dye bath, a drum rotatably mounted within said vat, means for guiding a web of material to be dyed onto 45 said drum, a supply-roll, an arm for supporting the same in a position to deliver the web to said guiding means, a second arm, a delivery-roll supported thereby arranged to receive the web after passing around said drum and arranged to be rotated when said drum rotates, and means for holding either of 50 said arms fixed.

55 6. In dyeing apparatus or the like, in combination, a vat for the dye bath, a drum rotatably mounted within said vat, means for guiding a web of material to be dyed onto 60 said drum, a supply-roll, an arm for supporting the same in a position to deliver the web to said guide, a second arm, a delivery-roll supported thereby arranged to receive the web after passing around said drum and arranged to be rotated when said drum rotates, means for holding either of 65 said arms fixed, and a guide-roll adjacent said delivery roll for supporting the same and for rotating said delivery-roll to wind up the web thereupon.

7. In dyeing apparatus or the like in combination, a vat for the dye bath, a drum rotatably mounted therein, a supply guide 70 roll adjacent said drum, a supply-roll from

which the web passes to be dyed around said supply guide roll and around said drum, a delivery guide-roll adjacent said drum and receiving the web therefrom, a delivery roll adjacent said delivery guide-roll upon which the web winds, and means for holding the axis of either said supply-roll or said delivery-roll fixed. 75

8. In dyeing apparatus or the like in combination, a vat for the dye bath, a drum rotatably mounted therein, a supply guide-roll adjacent said drum, a supply-roll from which the web passes to be dyed around said supply guide-roll and around said drum, a delivery guide-roll adjacent said drum and receiving the web therefrom, a delivery-roll adjacent said delivery guide-roll upon which the web winds, members for movably supporting said supply-roll so that said supply-roll may lie adjacent to and in contact with its corresponding guide-roll, and members for movably supporting the delivery-roll so that said delivery-roll can be held adjacent its corresponding guide-roll, and means for holding said roll supporting 85 members fixed or loose.

9. In dyeing apparatus or the like, in combination, a vat for the dye bath, a drum rotatably mounted within said bath, a pair of guide-rolls mounted over said drum and adapted to guide the web to be dyed in passing onto or from said drum, a pair of rolls upon which the web may be wound, and adjustable arms for supporting said last named rolls and arranged so that said last named rolls may come in contact with 90 said guide-rolls respectively.

10. In dyeing apparatus or the like, in combination, a vat for the dye bath, a drum rotatably mounted within said vat, a pair of guide-rolls mounted over said drum and adapted to guide the web to be dyed in passing onto or from said drum, a pair of rolls upon which the web may be wound, and adjustable arms for supporting said last named rolls and arranged so that said last named rolls may come in contact with 105 said guide-rolls respectively, said guide-rolls being arranged with their peripheries adjacent to the periphery of said drum, and means for supporting said guide-rolls so that a downward pressure on one of said guide rolls raises the opposite roll slightly from contact with said drum. 110

11. In dyeing apparatus or the like, in combination, a vat for the dye bath, a drum rotatably mounted within said vat, means for guiding the web to be dyed onto said drum and away from the same, a pair of rolls upon which the web may wrap, arms 120 movably supporting said rolls, counter-weight levers associated with said arms and adapted to carry counterweights to counter-balance the weight of the web on either of said rolls, and a clamping device associated 125 130

with each roll for clamping the supporting arms thereof in a fixed position.

12. In dyeing apparatus or the like, the combination of a delivery roll for a web, 5 and means tending to counter-balance the weight of said roll, and exerting greater power on said roll as the web is gradually wound thereupon and as said roll becomes heavier.

10 13. In dyeing apparatus or the like, the combination of a delivery roll for a web, and means tending to counterbalance the weight of said roll, and exerting greater power on said roll as the web is gradually 15 wound thereupon and as said roll becomes heavier, and means for compensating for differences in weight of goods.

14. In dyeing apparatus or the like the

combination of a delivery roll for a web, counterbalancing means, and means for adjusting the counterbalance weight to compensate for the difference in weight of goods. 20
